CEILING PANEL

Thomas R. Smith, Providence Township, Lancaster County, Pa., assignor to Armstrong Cork Company, Lancaster, Pa., a corporation of Pennsylvania

Filed Aug. 18, 1964, Ser. No. 81,332

Term of patent 14 years

(Cl. D18—2)

Fig. 1

I claim:

The ornamental design for a ceiling panel, substantially as shown.
